UNITED STATES PATENT OFFICE.

HENRY M. SHEER, OF QUINCY, ILLINOIS, ASSIGNOR OF ONE-HALF TO JOHN C. DUSSAIR, OF SAME PLACE.

HAME-FASTENER.

SPECIFICATION forming part of Letters Patent No. 622,084, dated March 28, 1899.

Application filed June 27, 1898. Serial No. 684,568. (No model.)

To all whom it may concern:

Be it known that I, HENRY M. SHEER, a citizen of the United States, residing at Quincy, in the county of Adams and State of Illinois, have invented certain new and useful Improvements in Hame-Fasteners; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to a rope-fastener for hames; and my object is to produce a more simple, cheap, durable, and easily-operated device than any hitherto invented.

To this end my invention consists of a peculiarly arranged and constructed cleat around which a tie-rope is adapted to be wound, together with certain other features, which will be more fully described hereinafter, and pointed out in the claims.

In the accompanying drawings, Figure 1 is a view in perspective of the lower portion of a horse-collar and the hames, showing my improved fastener applied thereto. Fig. 2 is an enlarged longitudinal sectional view through the cleat and its attached hook, the cord *h* being shown detached. Fig. 3 is a transverse section on line 3 3 of Fig. 2, and Fig. 4 is a longitudinal sectional view of the hook *b*.

The reference-letters *a* and *b* represent two hooks adapted to engage links *c* on the lower ends of the hames *d*, which embrace the collar *e*. The hook *b* on the right-hand side consists of an integral piece of cast metal, provided with a rope-receiving hole *f*, passing through its shank *f'* in a direction at right angles to the throat of the hook. The left-hand wall *f''* of the hook is arc-shaped and grooved to receive the cable or rope *h*, and the shank *f'* tapers as it extends away from the hook portion in order to lie more closely against the collar. The shank *g* of the opposite hook *a* is provided with a dovetail socket *g'*, adapted to receive and hold the looped end *h'* of the tie-rope *h*. The free end of the rope is also provided with a knot *h''*. On the front face of the shank *g* is riveted a cleat *k*, consisting of a thin concavo-convex casting sub-

stantially circular in general outline. From four equidistant points of the edge of the cleat project two guide-lugs *k'* and *k''* and also two hooks *l* and *l'*. The guide-lug *k''* is curved upward in the arc of the curvature of the cleat and is longer than the lug *k'*, which overhangs the inwardly-extending end of the hook *a*.

The hooks *l* and *l'* project far enough inward to engage and hold the rope when wrapped around the cleat *k*, and their outer portions are provided with divergent guides *l''*.

In operating the foregoing mechanism the hook *a*, to which is secured the cleat *k*, is entered into one of the links *c*, with its back against the collar. The hook is then caused to clasp the ring or link to a certain extent by clenching or otherwise in order to prevent its possible unhooking. Hook *b* is then placed in the link *c* of the other hame in a position corresponding to that of hook *a*; but there is this difference—to wit, hook *b* is not clenched, but left open. The fastening is now effected by drawing the cord as tightly as possible and wrapping it around the inside of the cleat, first over lug *k''*, thence over lug *k'*, following which it is drawn over hooks *l* and *l'* in the order named, the cord thus assuming the position indicated in Fig. 1, with the end or knot *h''* depending in convenient position to be manipulated. To unfasten it, the cord may be pulled upward against the inclined surface *l''* of the hook *l'*, causing that part of the cord which is caught beneath the hook *l'* to be forced out from under it, when the cord is unwound in the reverse direction from that in which it is first secured and the hames are loosened. It will be seen that the dished cleat and the projecting guide-lugs around its edges serve to greatly facilitate the quick wrapping of the rope about the cleat in the operation of fastening or tightening the hames.

Having thus described my invention, what I claim as new, and desire to secure by Letters Patent, is—

1. In a hame-fastener, the combination with a pair of hooks, and a flexible connection passed from one hook to the other, of a cleat secured to one hook, said cleat having radial projections or arms part of which terminate in downwardly or outwardly projecting lugs

and the remainder in upwardly or inwardly projecting hooks, the outer edges of said hooks having inclines which lead to their extreme edges to facilitate the unhooking of the flexible connection from the cleat.

2. The combination with a hook having a split tapering socket in its shank, said socket being struck up from the metal in the shank, and a flexible connection, one end of which is held in this socket, of a cleat secured to

this hook, said cleat having a series of radially-projecting arms, a portion of which terminate in lugs and the remaining portion in hooks.

In witness whereof I affix my signature in presence of two witnesses.

HENRY M. SIEER.
